UNITED STATES PATENT OFFICE

WILLARD A. MARCY, OF SYRACUSE, NEW YORK, ASSIGNOR TO THE LAMSON COMPANY, OF SYRACUSE, NEW YORK, A CORPORATION OF MASSACHUSETTS

VERTICAL CONVEYER

Application filed January 31, 1930. Serial No. 424,854.

This invention relates to conveyers and more particularly to conveyers of the elevator type the loads of which are automatically discharged at various stations predetermined by the location of the loads thereon.

The primary object of this invention is to provide an elevator having cars each of which includes compartments so that a plurality of separate loads may be carried for discharge at predetermined stations along the path of travel of the cars.

A further object of the invention is to provide ejector mechanism at the various stations whereby the loads may be discharged in combination with elevator cars provided with compartments, which ejector mechanisms are automatically operated by the cars to discharge from the cars the loads intended for the various stations.

Another object of this invention is to provide along the path of travel of the elevator cars, stations each including car unloading and loading means whereby loads supplied to the cars at a central loading station may be delivered to the various stations and other loads picked up for delivery to a central receiving station.

Other objects will appear from a consideration of the specific embodiment of the invention set forth in the following specification and in the drawings which form a part thereof and in which:

Figs. 1 and 1^a are front elevations of a portion of an elevator embodying this invention;

Figs. 2 and 2^a are side elevations thereof;

Fig. 3 is an enlarged sectional view taken along the lines 3—3 of Fig. 2 illustrating the main loading and unloading stations;

Fig. 4 is an elevation of an elevator car;

Fig. 5 is an enlarged side elevation of the main unloading station;

Fig. 6 is a plan view thereof;

Fig. 7 is a side elevation of a typical outstation having loading and unloading means;

Fig. 8 is an enlarged side elevation showing the ejector mechanism at such outstation;

Fig. 9 is a rear elevation of the ejector mechanism; and

Fig. 10 is a plan view of the unloading means of a typical outstation.

In Figs. 1, 1^a, 2 and 2^a there is illustrated somewhat diagrammatically an elevator embodying this invention and comprising a suitable casing 20 which defines an elevator well and in which operate a pair of endless chain belts 21 which travel over the usual head and foot sprocket wheels 22 and 23, respectively. The head sprocket wheels are suitably driven by a motor 24 which operates through any desired type of gearing. The casing 20 is preferably rectangular in conformation and comprises uprights 25, preferably angle irons, which are connected at suitable places by cross braces 26. Carried by the cross braces 26 are annular uprights 27 which define guideways 28 in which portions of the elevator cars travel as will be pointed out below.

The elevator cars 30 comprise end plates 31 which are suitably connected at the bottom by a plurality of crossrods 32. Each end plate 31 terminates at its upper and its lower end in a cylindrical boss 33 which, as is clearly shown in the drawings, extends into guideway 28 defined by the angular uprights 27. Projecting through the boss 33 at the upper end is the pin 34 which is secured to the links of the belt 21, as shown particularly in Fig. 4. Mounted upon the crossrods 32 are a plurality of spaced upright partitions 35 which divide the space between the end plates 31 into a plurality of compartments 36 one being allocated to each outstation B. A roller or button 37 projects outwardly from one end plate 31 for a purpose which will be disclosed hereinbelow. The rods 32 thus constitute trays provided by the partitions 35 with a plurality of load supporting spaces or compartments, which predetermine the destination of the load therein.

As pointed out above, this type of elevator is particularly adapted for carrying charts, records or other material from a central station A to any desired outstation B, and it will be understood that the charts to be sent from the central station to any particular outstation will be placed in the compartment or

compartments 36 of the car allocated to that outstation.

The main loading station A comprises a loading platform made by pairs of shelves 40 and 41 suitably spaced so that the cars travel freely between them. As indicated in Fig. 3, the pairs of shelves cooperate to provide a plurality of loading holders in which the material to be delivered to the various outstations may be placed. Each shelf is provided with upstanding walls 42 on three sides, the inner side being open so that each pair of shelves cooperates to support the charts or other records across the path of travel of the cars in such position that they will be picked up by the cars as they pass between the shelves in their upward travel. Each compartment of each car registers with a particular pair of shelves so that the material in any specific pair will always be carried by the cars in the same compartments.

The outstations B each comprise an unloading means 45 and a loading means 46 shown particularly in Figs. 7, 8, 9 and 10. The unloading means 45 is below the loading means 46 and includes a supporting post 50 which is secured to an angle bar 51 carried by two of the cross braces 26. Pivotedly mounted on the post 50 is an arm 52, the inner end 53 of which projects into the path of travel of the car and is contacted by each roller 37 on the end wall thereof. The outer end 54 of the arm 52 is pivotally connected by a link 55 to an arm 56 fixed upon a rock shaft 57 supported at one end in a boss 58 formed at the lower end of the post 50.

Projecting from the arm 56 is a second arm 59 to which is secured one end of a spring 60, the other end being attached to a button 61 projecting from one side of the post 50. The shaft 57 is supported at its other end in bearings 62 mounted on the angle bar 51. Fixed on the shaft 57 is an ejector arm 63, which may be as shown in Fig. 8, of spring material. The ejector arm 63 is secured adjacent its lower end to a squared portion 64 of the shaft 57 by a set screw 65. Mounted on the elevator casing at each station is a box 66 or other receptacle into which the ejected material will be thrown by the ejector arm 63.

The ejector arm 63 is so positioned and mounted at each station that it is in alignment with a particular compartment and may swing between the pair of adjacent partitions forming such compartment when the end 53 of the arm 52 associated with the ejector arm 63 and normally extending into the path of travel engages the roller 37 on each approaching car. The arms 63 at the several stations register with different compartments so that the load in the compartment with which an arm 63 registers is ejected when the car reaches the station to which that compartment is allocated. The lengths of the

shafts 57 vary as desired so that the ejector arm 63 at each station is properly located.

The normal position of the ejector mechanism at each station B is that shown in Fig. 7 of the drawings with the arm 52 extending into the path of travel of the cars and the arm 63 out of such path. This position is determined by a bracket 67 projecting from the post 50 and carrying a bumper 68 on which the arm 52 rests. The spring 60 obviously acts as soon as the roller 37 has released the arm 52 to return the arms to such position and maintain them therein so that the roller 37 of the next car will engage the arm 52. A depending spring plate 69 below the box 66 acts to protect any portion of the load that may project from the car. The particular embodiment here shown provides one compartment of each car for each station B and accordingly there is only one ejector arm 63 at each station. It will be understood however that under certain conditions more than one compartment might be required for a station and in such case additional ejector arms would be necessary.

The loading means 46 comprises a pair of shelves 70 and 71 which are similar to the shelves 40 and 41, previously described. These shelves are pivotally mounted at their outer ends on brackets 72, 73 carried by cross bars 74, 75 as shown in Fig. 7. It will be understood of course that the shelves 70 and 71 are so located in the elevator well that the charts placed therein are removed by the cars being picked up in the compartments thereof allocated to that particular station from which compartments any loads have just previously been ejected by the arms 63 as pointed out above. The various loading and unloading operations above mentioned all take place during the upward travel of the elevator cars.

Any obstruction which the cars might meet would probably be at the various loading means of the outstations and for that reason the shelves 70 and 71 are pivotally mounted so that while the shelves normally rest upon stops 76 (Fig. 7), they will swing outwardly into the dotted line position of Fig. 7 in case of any congestion and permit the car to pass freely without interrupting the travel of the chain belts 21.

As each car reaches the unloading station C on its downward travel, the contents of all the compartments 36 therein are discharged into a chute 80 by means of an ejector mechanism 81 (Figs. 5 and 6). Suitably supported in a journal 82 fixed upon a cross brace 26 is a rock shaft 83 which carries, at one end, an arm 84 projecting into the path of travel of the roller 37 on each car. To the other end of the rock shaft 83 is secured an arm 85 connected by a link 86 with an arm 87 fixed on a rock shaft 88. The rock shaft 88 is carried by a plurality of brack-

ets 89 fixed on one of the cross braces 26 and extending completely across the elevator well. Fixed upon the rock shaft 88 are a plurality of ejectors 90 which are so spaced that each travels through a compartment in the elevator car. Each ejector 90 is mounted adjacent its upper end on a squared portion 91 of the rock shaft 88 by a set screw 92. On the rock shaft 88 is secured an arm 95 which extends below the angle bar 26 and is preferably provided with a pad 96. This arm 95, as can readily be seen from an examination of Fig. 5, limits the movement of the rock shaft 88 in one direction. A spring 97 secured at one end to an eye 98 fixed on the arm 95 and secured at its other end to the elevator casing in any desired manner insures the return of the ejectors to the normal position shown in Fig. 5 with the pad 96 in contact with the cross brace 26. The chute 80 may be given the particular conformation shown in Figs. 1 and 2 so that the ejected material all passes to the receiving station D on the second floor adjacent the central loading station A.

From the description above given it will be obvious that in the specific embodiment selected for illustration, the records to be sent to the various departments are loaded into the proper holders at the central loading station A picked up in the proper compartments 36 by the first car passing through that station and carried to the destinations. As the cars pass through each of the out-stations B, the ejector arms 63 operates automatically, and any charts in the compartment allocated to that station will be ejected into the box 66. At the same time the operator at each of these outstations may place any material which he wishes to have returned to the central office on the shelves 70 and 71 so that they will be picked up in the empty compartment of the car as it passes between the shelves. The cars being pivotally mounted at their upper ends, as previously pointed out, will remain at all times in the upright position, and when they reach the unloading station C on their downward travel the contents thereof are automatically discharged into the chute 80 and delivered to the main receiving station D.

While one embodiment of this invention has been specifically described and shown it will be understood that the invention is not limited thereto and that other embodiments of the invention may be made without departing from the spirit and scope thereof as set forth in the following claims.

I claim:

1. The combination with an elevator which includes a car divided into a plurality of load supporting spaces and adapted to pass a plurality of stations disposed along the path of travel of the car of an automatic ejector means and a loading means at each of said

stations, the ejector and loading means of each station registering with a space on the car other than those with which such means at the other station register whereby the placing of a load in a particular space determines the station at which it will be ejected and another load may be supplied to the space at such station.

2. The combination with an elevator which includes a car divided into a plurality of load supporting compartments and adapted to travel by a plurality of stations disposed along the path of travel of the car of means at one station for loading any or all of such compartments, means at another station for ejecting the loads in all compartments so that the car leaves this station empty, and means at other stations for ejecting the loads in predetermined compartments and for supplying loads to such compartments.

3. In an elevator comprising means continuously traveling in a vertical plane, cars mounted thereon, each car having therein a plurality of horizontally arranged load-carrying compartments, and a station through which said cars pass, which station comprises means for removing the loads from a particular compartment of each car and means for subsequently supplying a load to such compartment.

4. In an elevator comprising means continuously traveling in a vertical plane, cars mounted thereon, each car having therein a plurality of horizontally arranged load-carrying compartments, and a station through which said cars pass, which station comprises means for removing the loads from a particular compartment of each car and means for subsequently supplying a load to such compartment, said load-removing means including an ejector automatically actuated by each car to pass into such compartment.

5. In an elevator comprising means continuously traveling in a vertical plane, cars mounted thereon, each car having therein a plurality of horizontally arranged load-carrying compartments, and a station through which said cars pass, which station comprises means for removing the loads from a particular compartment of each car and means for subsequently supplying a load to such compartment, said load supplying means comprising a pair of spaced shelves mounted in the path of travel of the cars and adapted to pass through such compartments of the cars.

6. In an elevator comprising means continuously traveling in a vertical plane, cars mounted thereon, each car having therein a plurality of horizontally arranged load-carrying compartments, and a station through which said cars pass, which station comprises means for removing the loads from a particular compartment of each car and means for subsequently supplying a load to such com-

partment, said load-removing means including an ejector automatically actuated by each car to pass into such compartment, and said load-supplying means comprising a pair of spaced shelves mounted in the path of travel of the cars and adapted to pass through such compartments of the cars.

7. In an elevator comprising means continuously traveling in a vertical well, cars mounted thereon and having a load carrying compartment therein, and a station through which said cars pass, which station comprises means for removing loads from the successive cars and means for subsequently supplying a load to such cars.

8. In an elevator comprising means continuously traveling in a vertical well, cars mounted thereon and having a load carrying compartment therein, and a station through which said cars pass, which station comprises means for removing loads from the successive cars, and means for subsequently supplying a load to such car, said load removing means including an ejector automatically actuated by each car to swing into the compartment and remove the contents therefrom.

9. In an elevator comprising means continuously traveling in a vertical well, cars mounted thereon and having a load carrying compartment therein, and a station through which said cars pass, which station comprises means for removing loads from the successive cars, and means for subsequently supplying a load to such cars, said load removing means including an arm pivotally supported upon the well frame and extending into the path of travel of the cars, an ejector pivotally supported upon the well frame, and normally out of such path of travel, means connecting the arm and ejector whereby upon the actuation of the arm by a passing car the ejector is swung into the compartment to remove the contents therefrom.

10. In an elevator comprising means continuously traveling in a vertical plane, cars mounted thereon, each car including a tray and plurality of spaced partitions by which load carrying compartments are made, stations through which said cars pass upon their upward and downward travel, the first station passed in the upward travel including means for supplying loads to any or all of the compartments in the car, the last station passed in the downward travel including means for automatically removing the loads in all such compartments, and the intermediate stations each comprising means for removing the load in a particular compartment and for thereafter supplying loads to such compartment.

11. An elevator car adapted to be supported upon chain belts and comprising end plates, cross rods connecting the end plates and forming a tray, and partitions carried by said rods which divide the space between the

end plates into load carrying compartments.

12. An elevator car adapted to be pivotally supported upon chain belts for travel upwardly and downwardly in a well, said car comprising end plates, cross rods connecting the end plates and forming a tray, partitions carried by said rods which divide the space between the end plates into load carrying compartments, and bosses on said end plates by which the cars are pivotally secured to said chain belts.

13. An elevator car adapted to be pivotally supported upon chain belts for travel upwardly and downwardly in a well, said car comprising end plates, cross rods connecting the end plates and forming a tray, partitions carried by said rods which divide the space between the end plates into load carrying compartments, and bosses on said end plates by which the cars are pivotally secured to said chain belts, said bosses entering vertical guideways in the well to hold the tray horizontal during the travel of the car.

Signed by me at Syracuse, N. Y., this 28th day of January, 1930.
